HOUSING FOR AN ELECTRICAL TRANSFORMER

John N. Davis, Pittsfield, Mass., assignor to General Electric Company, a corporation of New York

Filed Jan. 20, 1964, Ser. No. 78,276

Term of patent 14 years

(Cl. D26—15)

Fig. 1.

Fig. 2.

Fig. 3.

Fig. 4.

FIGURE 1 is a top view of a housing for an electrical transformer showing my new design;

FIGURE 2 is a front elevation view;

FIGURE 3 is a perspective view showing the back and one side; and

FIGURE 4 is a perspective view showing the front and other side thereof.

The dominant features of my new design are shown in solid lines in the drawing.

I claim:

The ornamental design for a housing for an electrical transformer, as shown and described.
